UNITED STATES PATENT OFFICE.

OSCAR HULTBERG, OF SEATTLE, WASHINGTON.

WAVE MOTOR.

1,423,115.

Specification of Letters Patent. Patented July 18, 1922.

Application filed April 11, 1921. Serial No. 460,452.

To all whom it may concern:

Be it known that I, OSCAR HULTBERG, subject of the King of Sweden, residing at Seattle, in the county of King and State of Washington, have invented certain new and useful Improvements in Wave Motors, of which the following is a specification.

This invention relates to apparatus for utilizing the power of sea-waves; and its 10 object is the provision of apparatus of this character which will be of inexpensive, strong and durable construction and which will be efficient in use.

To these ends the invention consists in the 15 novel construction, adaptation and combination of parts hereinafter described and claimed.

In the accompanying drawings,—

Figure 1 is an elevational view partly 20 broken away and partly in section of a wave motor embodying the present invention. Fig. 2 is a detail sectional view of one of the devices shown in the other views for converting vertical reciprocatory motion into 25 rotary motion. Fig. 3 is a plan view through 3—3 of Fig. 1 with parts omitted. Fig. 4 is a sectional view through 4—4 of Fig. 3.

In said drawings the reference numeral 30 5 designates a mast of a polygonal shape in transverse section, which is secured at its lower end as by links 6 to stakes 7 which are rigidly engaged in the sea-bed indicated by 8.

35 Mounted upon said mast for relative vertical movements is a sleeve 9 to the lower end of which are connected stays 10 for maintaining the mast in a substantially vertical position. Said stays include extensible 40 spring elements 11 to accommodate axial movements of the sleeve.

Surrounding the mast 5 is an annular 45 floatative vessel 12 which is connected for oscillatory movements to said sleeve by providing a globular portion 13 on the latter to fit into a housing comprised of circular plates 14 secured to the vessel 12 as shown in Figs. 1 and 3.

Secured to said mast above and below said 50 sleeve, respectively, are collars 15 having eye elements 16 to which the stems 18 of coupling devices are pivotally connected by means of pins 19.

The arms 20 and 21 of complementary 55 coupling devices—that is to say, one above and the other below the sleeve 9—are respec-

tively connected by sprocket chains 20¹ and 21¹ which extend through openings 22 provided in the vessel 12. Said coupling devices, moreover, are disposed to have the associated pair of sprocket chains disposed to be in planes, so to speak, which are radial to the mast.

23 represents sprocket wheels, one for each pair of chains, and positioned between the same as shown in Fig. 1. The outer chain 20¹ of each pair engages the periphery of the respective wheel at the outer side of the same, and the complementary inner chains 21¹ are held in engagement with the inner 70 sides of the wheels by guide pulleys 24. Referring to Fig. 2, a wheel 23 is provided with teeth 25 of substantially triangular shapes extending from pockets 26 provided about the circumference of the wheel and 75 pivotally connected thereto by pins 27. Springs 28 serve to yieldingly retain the various teeth in their protruding positions whereby they are engaged by the chains to effect movements of the wheel in but one rotary direction—in other words, when a wheel travels downwardly but one of each pair of chains is operative and in travelling upwardly the other chain only is operative.

The wave impelled movements of the vessel 80 transmitted through the chains 20¹, 21¹ to the sprocket wheels is converted into energy by any suitable power generator such as electric motors or fluid compressor or pumps, indicated by 30, provided on the 90 vessel's deck. As illustrated the sprocket wheels are mounted upon shafts 31 which are respectively connected by trains of spur gears 32 with the generators 30.

In order, however, to overcome irregular 95 motion between the chains and generators and also to obviate shocks due to the intermittent action of the chains, the wheels 23 are desirably mounted for relative rotary movements on their shafts 31 and are operatively connected by springs 33, one end of each spring being secured to a wheel 23 and its other end is secured to a set collar 34 rigid with the respective shaft.

In operation, the waves impart vertical 105 motions to the vessel 12 approximating the difference between the elevations of the wave crests and troughs and also produce in the vessel oscillating motions due to the passage of waves.

As these various motions occur in the vessel, the several sprocket wheels 23 are accord-

ingly caused to ascend and descend relative to the respective chains 20¹ and 21¹. Said sprocket wheels are effected alternately by the chains 20¹ and 21¹ resulting in the sprocket wheels being intermittently rotated in corresponding direction to thereby actuate, through the respective driving mechanism, the several generators for producing power.

10 The intermittent rotary motions above referred to are converted into substantially continuous rotary motions at each of the generators through the power conserving action of the springs which operatively connect the wheels 23 to their respective shafts.

What I claim is—

1. In a wave-motor, the combination of a mast, means to maintain said mast substantially vertical, a floatative vessel, means for connecting said vessel to the mast to rise and fall with the waves, wheels provided on said vessel, cables extending through the vessel and connected above and below the same to said mast, means provided on said 25 wheels whereby the latter are caused by said cables to be rotated in the same directions during both the upward and downward wave impelled movements of the vessel.

2. In a wave-motor, the combination of a mast secured at its lower end, a sleeve mounted upon said mast, stays connected to said sleeve for maintaining the mast in substantially vertical position and affording movements to the sleeve axially of the mast, a floatative vessel tiltably connected to said sleeve, pairs of chains extending through apertures of said vessel and connected above and below the latter to said mast, sprocket wheels carried by the vessel for the respective pairs of chains, and means rendered

operative through the medium of said chains and wheels for converting the wave impelled motions of the vessel into power.

3. In a wave-motor, the combination of a mast secured at its lower end, a sleeve mounted upon said mast for relative axial motions, stays including spring elements connected to said sleeve for maintaining the mast in a substantially vertical position, a floatative vessel tiltably connected to said sleeve, pairs of chains extending through apertures of said vessel and connected above and below the latter to said mast, sprocket wheels provided on the vessel for the respective pairs of chains, and means rendered operative through the medium of said chains and wheels for converting the wave impelled motions of the vessel into power.

4. In a wave-motor, the combination of a floatative vessel, a mast extending centrally therethrough, a sleeve serving to connect said vessel to the mast for relative axial and rocking motions, a plurality of power generating mechanisms provided on said vessel, each of said mechanisms including a sprocket wheel having retractile teeth, a pair of spaced chains for each of said sprocket wheels, said chains being connected to the mast above and below said vessel and engaging the respective wheels at diametrically opposite sides of the latter to produce intermittent rotary motions to each wheel in both the upward and downward movements of each wheel.

Signed at Seattle, Washington, this 2nd day of April, 1921.

OSCAR HULTBERG.
